(57) **CLAIM**

The ornamental design for a hand held reamer holder, as shown and described.

DESCRIPTION

FIG. 1 shows a right perspective view of the hand held reamer holder;

FIG. 2 shows a left perspective view of the hand held reamer holder;

FIG. 3 shows a top view of the hand held reamer holder;

FIG. 4 shows a bottom view of the hand held reamer holder;

FIG. 5 shows a front side view of the hand held reamer holder; and,

FIG. 6 is a back view of the hand held reamer holder.

The broken lines showing a reamer is for the purposes of illustrating the environmental structure and forms no part of the claimed design.
